UNITED STATES PATENT OFFICE.

ALBERT SWARTZ, OF TOLEDO, OHIO.

TICKET ISSUING AND COLLECTING.

1,319,254.

Specification of Letters Patent.

Patented Oct. 21, 1919.

Application filed April 12, 1919. Serial No. 289,717.

To all whom it may concern:

Be it known that I, ALBERT SWARTZ, a citizen of the United States of America, residing at Toledo, Lucas county, Ohio, have invented new and useful Improvements in Ticket Issuing and Collecting, of which the following is a specification.

This invention relates to computing and verifying charges.

10 This invention has utility especially in ticket issuing at entrance and paying on departure, as in zone travel computation.

Referring to the drawings:

Figure 1 is a diagrammatic view of a 15 type of car to which this device may be adapted and in which the method may be readily used.

20 Figs. 2, 3, 4, 5, 6 and 7, are other types of cars or traveling vehicles to which the device, and the method of use, may be readily adapted.

Fig. 8 is a diagrammatic view of a system having isolated stations, or points for entrance and exit, so that the issuing and 25 collection of tickets may occur apart from the vehicle, as in instances of subways and elevated railways.

Fig. 9 is a detail view of mechanism of the apparatus adapted especially for use in 30 carrying out the method disclosed of zone handling for fares.

Fig. 10 is a wiring diagram of intercontrol for these ticket collection and issuing apparatuses.

35 Fig. 11 is a view of a ticket as issued and;

Fig. 12 is a view of such ticket as marked or charged by the collection apparatus.

In carrying out the invention it has special adaptation for use in those instances

40 where the rate of charge may vary according to the point of ingress and egress of an individual. This condition arises in its simplest form in the matter of transportation, especially as to travel between cer-

45 tain zones. As an instance of this, a street car 1 may be considered as having in its forward portion a station 2 for a motorman, operator or driver.

An entrance 3 at the rear may be past a station 4 for a conductor

50 in charge of the collection of fares and the conduct of the passengers in the car. In

this instance the conductor may issue a ticket or hand a ticket from issuing apparatus 5 as each person enters the car. The pas-

55 sage from the car may be by exit 5' adjacent collection box 6. This exit 5' is at

the rear of this car 1 and adjoining the entrance 3.

In adapting to the type of car having forward entrance 3 as shown by car 7 (Fig. 2) 60 the ticket issuing apparatus 5 may be stationed adjacent the motorman station 2, while the conductor station 4 may be disposed in the rear of the car adjacent the collection apparatus 6 in the vicinity of 65 exit 5'.

In the type of car 8 (Fig. 3) which has center entrance and exit in the same side of the car, the ticket issuing apparatus 5 may be disposed adjacent the entrance 3, 70 while the ticket collection apparatus 6 may be disposed adjacent the exit 5'. This general mode for adapting the method and apparatus of the device herein as shown in Fig. 3, may conform to the type of car 9 75 (Fig. 4).

In the type of cars 9 (Fig. 4) when used for front entrance as shown by car 10 (Fig. 5) the issuing apparatus 5 may be placed adjacent the motorman station 2 while the 80 collection box 6 may be located near the conductor station 4 at the center of the car 10 adjacent the side exit 5'.

In the type of car 11 (Fig. 6) which shows a front entrance 3 and adjacent thereto a front exit 5' the issuing apparatus 5 and the collection apparatus 6 are disposed adjacent the motorman station 2. This embodiment may readily be operated as a one man car. 90

Car 12 (Fig. 7) is similar in general structure to the car 11 (Fig. 6) but is designed to be operated by a conductor in addition to the motorman. The fare collection box 6 and the ticket issuing box 5 may be disposed adjacent the conductor station 4 near the front of the car and in the present instance shown as near the station 2 of the motorman.

In those instances of transportation where 100 the stations are isolated from the public, one may consider the showing (Fig. 8) wherein track 13 for cars or trains 14 extends from isolated station 15 to stations 16. The apparatus 5 may be placed at the entrances 105 of such stations and the apparatus 6 at the exits of such stations.

These ticket issuing and collecting apparatuses may be of some general type of ticket printing machine, for instance the type car- 110 ry 1211—E of The National Cash Register Co. As an individual entering, passes the

station of the apparatus 5, a pressure say by the conductor or attendant upon button 17, will result in the issuance of a ticket at chute 18, which may be taken by the one 5 entering. This ticket 19 is preferably designed to show the point of issuance and, as shown (Fig. 11) in its adaptation to transportation problems, there may be a zone or place location on the apparatus 6, as an indicator 20 which, in instances of fare handling may be a zone designation or a place designation. In the instances where these apparatuses are carried on a traveling vehicle it is desirable to shift the zones 10 as by pressing on a key 21, for the ticket issuing zone change station apparatus 5 and upon a key 22 for the ticket collecting apparatus 6. When these ticket issuing and ticket collecting apparatuses are 15 used in non-traveling relations as in subways or on elevated lines at isolated or in-closed stations, the question of shifting the zone indication does not rise and the apparatus in itself may be much more simple, 20 always disclosing the same showing for its station, as well as always printing the same.

In instances where the apparatuses are used upon traveling vehicles, it is desirable to have an interconnection control designation 30 between these apparatuses. In this interconnection control, the zone push button 21 at the ticket issuing station 5 may be provided with a conductor plate 23 on the under side thereof (Fig. 10). Accordingly on depressing 35 this button 21 electric current from lines 24, 25, to terminal 26 may pass through the plate 23 to terminal 27 and then by line 28 to terminal 29, coil 30 to line 31, as the other side of this supply for completing 40 current circuit in energizing the coil 30. The coil 30 thus draws core 32 thereinto, thrusting stem 33 carrying terminal roller 34 to push bar 35 having hinge connection 36 with the bottom of the push button 22 at 45 the collection station 6. This bar 35 is normally held against the roller 34 by spring 37. Accordingly, the bar 35 is thrust away from stem 38 of the push button 22. This pushing of the bar 35 against the stem 38 moves 50 this bar 35 so that depression of the button 22 into the housing of the station 6 may occur for the bar 35 is clear of the housing. However, this position for the bar 35 will continue without a holding of the button 55 21 at the issuing station 5 for the stem 32 carries a terminal 39 which in the travel of the core 33 into the coil 30 connects up for current flow from the line 24 through line 40 terminal 41 to pass this terminal 39 to 60 terminal 42 thence by line 43 to the terminal 29 thereby maintaining the coil 30 energized. The pressure on the issuing station button 21 may occur as the car makes its last stop in a zone. The change at the 65 collection station 6 may not occur iden-

tically with this change at the issue station 5, for while this zone change may occur manually it is preferably automatically operated from the closing of exit door 44 having cam 45 operate against the arm 46 70 having pivot bearing 47. About this pivot bearing 47 is a coil spring 48 bearing against the arm 46 to make a yieldable connection for actuating arm 49 resting upon the button 22 of the station 6. Accordingly when this 75 exit door 44 is closed the arm 49 yieldably acts upon the button 22 and as the bar 35 is clear of the housing 6 the button 22 may be depressed to effect a zone station indication change corresponding to the change 80 of station as indicated at the issue station. This permits the passengers going out at the last station of the zone to be charged for that zone while any passenger passing out at the next station has the zone indication of the collection station 6 show the zone corresponding with the issue station 5 so that the fare collector may make a charge 85 accordingly. As the button 22 is depressed cam 50 wedges the roller 34 out to move the 90 bar 39 to break the circuit deenergizing the coil 30. Accordingly on the recoverance travel of the button 22 the bar 35 is again in locking position. These charges may be determined by comparison of the location on 95 the issue station ticket or check 51 as a distance deduction from the collection station reading. This difference may show the number of zones which the passenger has traveled. The indication on the station 6 as 100 well as the indication on the station 5 permits the passenger to check up whether or not the amount one is charged is in accordance with the indication of issue ticket and the collection station. The deposit of the 105 ticket in the collection station 6 in the chute 52 results in such ticket having a printed notation thereon, as shown by ticket 53 (Fig. 12). This is a verification for the carrier company or operator to check up with the 110 conductor, so there is a double check, one for the passenger aboard who checks up his fare to be paid the conductor and the other a checking up for the company between tickets turned in and fares turned in. The money 115 for the fare may be deposited in a box or may be given to the conductor as may be found desirable.

There is accordingly provided by the invention herein a simple means for zone fare collection as a pay-exit proposition in which the ticket is issued for identification at the entrance station. The identification data not only at the issuing station but also at the collection station is preferably something 125 which may be checked up readily and be visible to the passenger or the person being served. With ease the apparatus and method may be adapted to electric passenger service wherein the fare may vary accord- 130

ing to the distance one is carried. In disposing the issuing and collection apparatus as here described there may be quick handling of traffic in a simple convenient 5 manner.

What is claimed and is desired to secure by Letters Patent is:—

1. A ticket issuing machine for ticket issuing designation, a ticket receiving machine 10 for ticket receiving designation, said receiving machine having a way for receiving a ticket, and interconnected designation control means between said machines permitting independent ticket handling by said 15 machines.

2. In the handling of tickets, the combination of indication mechanism for a designation of an issuing designation, and collection recording means for checking of said issuing 20 designation in totaling said ticket charge.

3. In the determination of fare, the combination of entry designation mechanism with exit designation mechanism for disclosing relations therebetween in fare 25 collection.

4. The combination for determining zone fare totals including entrance disclosing designation mechanism having means for issuing a ticket, and exit designation mechanism for marking said ticket.

5. A zone fare apparatus for passenger transporting lines including ticket issuing designation means coacting for an entrance zone and a ticket collection designation co-

acting as zone designation means with the 35 issuing designation means whereby checking of issuing designation with collection designation may disclose distance for fare computation.

6. A zone fare apparatus for passenger 40 transporting lines embodying a traveling vehicle, ticket issuing and ticket collecting apparatus on the vehicle having respectively issuing and collecting designation means, said vehicle having an entrance way for incoming passengers to receive zone entrance designation tickets as determined by the ticket issuing designation means, and an exit way for outgoing passengers to have fare collected as checking up with zone indication at collection designation means. 50

7. A passenger car having an entrance way and an exit way, a zone designation ticket issuing apparatus at the entrance way and a zone designation ticket collecting apparatus at the exit way, said apparatus co-acting to mark a ticket for passenger and carrier verification as to entrance and exit to determine total for fare. 55

8. A ticket issuing pay-exit vehicle having 60 mechanism for issuing a ticket to disclose entrance zone, and collection mechanism for receiving and marking said entrance ticket with exit designation of collection zone as basis for charge computation. 65

In witness whereof I affix my signature.

ALBERT SWARTZ.
